UNITED STATES PATENT OFFICE.

ABRAHAM TEN BOSCH, N. J. ZOON, OF THE HAGUE, NETHERLANDS.

METHOD AND MEANS FOR REMOVING WATER FROM PEAT.

1,290,494.

Specification of Letters Patent.

Patented Jan. 7, 1919.

Application filed April 23, 1918. Serial No. 230,337.

To all whom it may concern:

- Be it known that I, ABRAHAM TEN BOSCH, N. J. ZOON, a subject of the Queen of the Netherlands, and residing at 10 Wattstraat, The Hague, the Netherlands, have invented certain new and useful Improvements in Methods and Means for Removing Water from Peat, of which the following is a specification.
- 10 The present invention relates to a method and means for forcing water from peat by the application of heat and pressure.
- It is known that water cannot be removed from peat exclusively by pressure even when
- 15 the highest pressure is employed, and I have found that the water will be rendered more readily expressible if the pulp of the peat has been treated by heat prior to compression.
- 20 The method according to the invention renders a continuous service possible and has all advantages connected to such service.
- The invention is adapted as well for the
- 25 expression of water from other materials of the same character as peat.
- My invention primarily consists in the method of forcing the peat pulp in a continuous flow against a high resistance
- 30 through a tower, in which the pulp on its way, is subjected to the heat-treatment preferably by steam having a pressure higher than the atmosphere, and of thereafter compressing the peat by the forcing pressure.
- 35 My invention further provides an improved apparatus or plant for carrying my above mentioned method into practice. A most convenient and suitable plant comprises a tower or a shaft having a steam
- 40 supply pipe connected to it and being provided below said steam supply with an outlet for the expressed water. The lower end of the tower is provided with a funnel having a discharge for the treated pulp. My
- 45 plant as just specified is extremely simple in construction and operation. All mechanical structures for applying the pressure required to force the peat continually through the inclosed space, *i. e.*, through the tower
- 50 and the discharge at its bottom are avoided and all disadvantages connected to said auxiliary means are thus obviated. The weight of the pulp itself causes a regular slow flow of the pulp to the discharge end of the
- 55 tower or shaft. In accordance with my invention, the height of the tower or the shaft

above the steam supply referred to is chosen so as to warrant a sufficiently heavy pressure by the peat in the upper part of the tower upon the treated pulp after passing 60 the steam supply, to express the water contained in the pulp through the outlet provided for this purpose and to force the pulp freed from water through the discharge opening. The height of the tower or shaft 65 may be made to suit the most effective temperature and pressure of the steam supplied.

The plant works entirely automatically and continuously and is very simple in operation.

70 The accompanying drawing illustrates diagrammatically my improved plant used for carrying out my method.

1. is a tower constructed from sheet steel or another suitable material. This tower 75 is open at the top end, *e. g.* it is not closed hermetically. It may be covered in such a manner that charging of the tower during service is not interfered with. The peat pulp is carried upward to the top of the 80 tower by means of a suitable carrier (not shown) and poured into the tower at the top end of same. In order to obtain the required pressure upon the lower layers of the pulp within the tower or to suit the requirements as to the temperature of the steam for attaining a proper treatment of the pulp the height of the tower is preferably approximately 160 feet. At some distance from the lower end of the tower a steam 85 supply piping 2 having a cut-off 3 is passed through the wall of the tower and extended into the interior of the latter by an elbow pipe 4. This pipe 4 is perforated over part 5 of its length in order to permit the 90 steam to enter the pulp.

95 Below the pipe 4 the wall of the tower is interrupted by a perforated cylinder 6, constructed as a grid and surrounded by a water reservoir 7. To the bottom of this reservoir 100 a water discharge pipe 8 is connected.

Below the perforated cylinder 6 the tower 105 is extended into a funnel 10 having a mouth-piece 9. Adjacent the discharge opening 11 of said funnel a slide 12 is mounted, operable by means of a rack 13, a pinion 14 and a hand-wheel 15 so as to cut-off the discharge or open same. The funnel 10 is bent, as shown in the drawing so that the peat freed from water leaves the tower in a horizontal 110 direction. The sectional area of the discharge is so dimensioned that the peat leav-

ing the mouth piece is in the form of a bar, which may be cut into lumps or briquets.

The plant operates as follows:

The tower 1 is constantly maintained full 5 of pulp. Through the piping 2 and the cut-off 3 steam is continually admitted to the pipe 4. The steam escaping through the perforations 5 finds its way upward through the pulp and renders the water more readily 10 expressible by heat treatment. The pressure upon the pulp next to the steam supply and to the water outlet is very considerable, *e. g.* with a tower of 160 feet high, and leaving the friction of the peat along the walls out 15 of account, said pressure would amount to approximately 70 lbs. per square inch. As a result steam of high temperature can be applied and an improved treatment is obtained owing to the steam of higher temperatures 20 having a more intensive effect upon the peat. The steam, rising through the pulp eventually is condensed in the higher layers of the same, thereby pre-heating the pulp in the top part of the tower.

25 After having been subjected to the heat treatment, the pulp passes to the perforated cylinder 6. Owing to the heavy pressure upon the peat in the range of the perforated cylinder, the water is forced out of the pulp 30 to the required extent and flows off through the openings in the cylinder 6, into the casing 7 discharging by means of the piping 8.

Pre-heating of the pulp in the tower can be improved by extending the water casing 35 7 upward, thus providing the tower with a water jacket in which the hot expressed water rises to be let-off at the top end through a piping or an overflow. Also the water flowing from the casing 7 may be used 40 for pre-heating purposes by mixing same with the fresh pulp to be charged into the tower if desired.

The peat freed from water is forced into the funnel 10 and is continually forced 45 through the discharge opening 11 into the atmosphere.

The funnel 10 and the discharge opening 11 are so dimensioned relative to the area of

the tower as to cause a sufficient counter-pressure opposing the weight of the peat 50 column within the tower, so that the pressure acting against the weight of the peat column compresses the peat and discharges the same in the shape of a hard bar, which may be cut into briquets or lumps. 55

As the peat is emerging from the tower at the bottom end, the tower is constantly charged at the top. The operation therefore is continuous resulting in increased capacity and efficiency of the plant. 60

Having now described my invention, what I claim and desire to secure by Letters Patent is:—

1. The method hereinbefore described of removing water from peat by heat treatment 65 which method consists in forcing the pulp of the peat in a continuous flow, against a heavy resisting power, through an inclosed space, in which it is subjected to heat treatment of steam with a pressure higher than 70 the atmosphere and thereupon freed from water by the forcing pressure.

2. A plant for carrying out the method hereinbefore described of removing water from peat by heat treatment, which plant 75 comprises a vertical tower of such dimensions that the weight of the column of peat pulp therein is sufficient to force the peat through the tower, a charging opening at one end of said tower, a steam supply connected 80 to said space, a water outlet past said steam supply and a discharge opening for the treated pulp freed from water past said water outlet.

3. A plant for carrying out the method hereinbefore described of removing water from peat by heat treatment, which plant 85 comprises an upstanding lengthy tower, a steam supply connected to the side wall of said tower, a water outlet underneath said 90 steam supply and a discharge opening beneath said water outlet presenting a high resistance to the pulp freed from water.

In testimony whereof I affix my signature.

ABRAHAM TEN BOSCH, N. J. ZOON.
